SILENT TUNING SYSTEM FOR RADIO- RECEIVERS

Alexander Senauke, New York, N. Y., assignor to
Hazeltine Corporation, Jersey City, N. J., a cor-
poration of Delaware

Application January 27, 1933, Serial No. 653,795

15 Claims. (CL 250—20)

This application relates to electrical tuning apparatus and it is particularly advantageous in broadcast receivers, although its application is not limited thereto.

5 In certain aspects my invention is an improvement on the apparatus shown and described in my Patent No. 1,839,419 entitled Radio receiver and on my applications Serial Nos. 527,673 and 589,812, Patent #1,961,574 granted June 5, 1934, 10 and as to certain parts thereof is a continuation in part of said applications.

In accordance with my invention, I provide a system by means of which the radio receiver or other apparatus in which the system is embodied, 5 is rendered unresponsive, at least in part, to incoming electrical impulses and disturbances, during times when the receiver is not tuned to a desired signal, and is rendered completely responsive to incoming signals merely by the adjustment of the tuning control to a frequency at which the receiver is at or near resonance with an incoming signal of predetermined strength.

In accordance with another aspect of my invention I obtain this result either without requiring the use of any tubes or the like, other than those ordinarily provided for amplification and detection purposes in the receiving apparatus, or by the use of a gaseous discharge tube.

In accordance with still another aspect of my invention, I combine a system of the class described with systems such as those described and claimed in my patent and applications above referred to, in which a visual indicator, such as a lamp, is energized at the settings of the tuning indicator which correspond to exact resonance with incoming signals.

Among the various objects of my invention, it is an object to provide a radio receiving system in which noises, interference and the like, which might otherwise be heard, are suppressed during the transition period of tuning from one station to another.

It is a further object of my invention to provide a system of the class described in which the result is obtained without the necessity of providing additional vacuum tubes in or associated with the receiving apparatus.

It is a further object of my invention to provide such a system which is capable of adjustment so as to exclude not only noises and various types of undesired electrical disturbances, but also to exclude undesired signals, the strength of which may be insufficient to be pleasing to the listener.

It is a further object of my invention to pro-

vide a system of the class described utilizing a visual indicator, such as a lamp, for giving a light signal to show when the receiving apparatus is tuned to exact resonance with the incoming desired signal.

It is still a further object of my invention to provide such a system in which a gaseous discharge lamp may be utilized to accelerate or magnify the action of the apparatus in changing from responsive to unresponsive condition and vice versa.

Still other objects and advantages of my invention will be apparent from the specification.

The features of novelty which I believe to be characteristic of my invention are set forth with particularity in the appended claims. My invention itself, however, both as to its fundamental principles and as to its particular embodiments, will best be understood by reference to the specification and accompanying drawings, in which

Fig. 1 represents one embodiment of the circuit according to my invention;

Fig. 2 is a characteristic curve of response of an electronic discharge tube which may be utilized in accordance with my invention;

Figs. 3, 4 and 5 are modified forms of circuit in accordance with my invention;

Fig. 5 is a partial circuit diagram of a modification of Fig. 4;

Fig. 6 is a partial circuit diagram of a modification of Fig. 1; and

Fig. 7 is a partial circuit diagram of a modification of Fig. 3.

Referring now more particularly to Figs. 1 and 2, I have shown in Fig. 1 a circuit arranged in such manner that the voltages developed in the normal action of the circuit will produce a silencing of the receiver when the signal input is less than a predetermined amount.

In this figure I have shown a circuit diagram of a so-called tuned radio frequency amplifier followed by a detector and audio amplifier, but it will be understood that my invention is not limited to such receivers, but may also be applied in other types of receivers, such as so-called superheterodyne receivers which may be considered as acting in essentially the same manner and subject to the same type of control insofar as regards the principles of my invention.

1 designates a signal collecting device of any suitable type, such as an antenna, connected to the coil 2, grounded as at 3. Coil 4 may be coupled to coil 2, and may form part of the first tuned circuit of the receiver, which is completed by blocking condenser 6 and tuning condenser 5.

The tuned circuit so formed may be grounded, as indicated, and likewise connected to the control electrode 9 of the vacuum tube 7, which may comprise an anode 8, a cathode 10 and, if desired, a heater 11 for heating the cathode 10 to electron emitting temperature.

I do not desire to limit myself to the use of any particular type of thermionic vacuum tube, since a number of well known types of tubes will operate as desired, and it will be understood that types of vacuum tubes other than that shown may be utilized if desired, such for example as the so-called screen grid tube. For purposes of simplicity I have omitted portions of the hearing circuits of the various tubes, since these arrangements are well-known in the art and form per se no part of my invention.

The cathode 10 of the tube 7 may be connected to ground through condenser 12 for a purpose which will be later explained, and the condenser may be shunted by resistance 12a. The output of tube 7 is passed through coil 13 which is in turn coupled to coil 14, and associated with the coil 14 are the blocking condenser 16 and the turning condenser 15, forming another tuned circuit.

A second vacuum tube 17 is similarly associated with the second tuned circuit and the output of tube 17 is passed through coil 19, which is coupled to coil 20. Vacuum tube 25 may in this case be the same type of tube employed in the preceding stages, or a different type, but it may, and in some cases preferably will be, arranged for operation as a Fleming valve, the control electrode 26 and the anode 24 being connected together for this purpose, and the signal being impressed between the cathode 27 and the electrodes 24 and 26, the input circuit consisting of coil 20 and resistance 21. Resistance 21 may be shunted by condenser 22.

The low potential side of coils 4 and 14 may be connected together and to conductor 70, and interposed in this conductor 70 I may provide resistance 53. The low potential end of coil 20 may be connected to conductor 70 on the opposite side of resistance 53, through an interposed inductance 23, and conductor 70 leads to condenser 29, thence through resistance 30 to conductor 60 which, in turn, is connected to the blade of switch 61, which I term the noise gate switch, the function of which will be described hereafter.

The lower terminal of resistance 30 may be connected to ground through condenser 31, as indicated, and tap 32 may be provided as a manual volume control for varying the magnitude of impulses impressed on the first audio frequency amplifying tube 33, the output of which may be fed through transformer 34 to the input of a second audio frequency amplifying stage herein diagrammatically indicated as so-called push-pull and comprising tubes 35 and 36, whose output is combined by transformer 37 and supplied to a suitable indicating device such as the voice coil of a loud speaker 39 operating in a magnetic field produced, for example, by coil 38.

Since the construction and operation of the audio frequency amplifier subsequent to tube 33 and loud speaker herein diagrammatically indicated is well-known to and understood by those skilled in the art, and constitutes per se no part of this invention, the same is not shown or described in detail.

The apparatus thus far described may be energized in any suitable manner as by batteries or

other source of direct current, but customarily a so-called power pack will be employed for operating it from alternating current, and this may take the form indicated, in which 40 is the primary of the power transformer having a number of secondaries 41, 42, 43 and 44 for providing alternating currents of different voltages.

45 indicates a thermionic rectifier of the full wave type, the filament of which is energized from secondary winding 42, and 46 represents a 10 choke interposed on the positive side of the rectified current line for the purpose of smoothing out fluctuations. 47 and 48 are filter condensers connected between the positive and negative sides of the circuit for the further smoothing out of 15 fluctuations, and since this construction is well understood in the art no further description is believed necessary.

Transformer secondaries 43 and 44 may be utilized to supply raw alternating current to the 20 filaments of the various tubes, and the mid-point of winding 44 may be grounded through resistance 67 shunted by condenser 68.

The lower terminal of coils 13 and 19 may be connected together to conductor 50 and resistor 51 grounded through condenser 18 and to a suitable point on resistances 55, 56 and 57 which are connected between the positive side of condenser 49 and ground, thus providing the desired voltage for the anodes of tubes 7 and 17.

The field coil 38 of the loud speaker may be connected through conductor 66 to the lower terminals of condensers 48 and 47 and its other terminal grounded.

Connected to the common point of resistances 55 and 57 I may provide a conductor 63 leading to noise gate switch contact 63a.

The noise gate switch 61 in one position may engage contact 63a and in the other position may engage a contact 64a connected to conductor 66, 40 grounded through resistance 65.

For the purpose of providing for magnified noise control and for a visual tuning indication, if desired, I may provide the gaseous discharge tube generically designated as 70, which is preferably a tube of the type obtainable on the market under the name "Tun-A-Lite", consisting, in one form, of an envelope containing gas at a relatively low pressure, such as neon at a pressure of a few millimeters, and having within the envelope a short cathode 71, a short anode 72, and a long cathode 73. The anode 72 is connected to the lower potential point of resistance 51 as indicated, the short cathode through limiting resistance 74 to conductor 66, and the long 55 cathode to conductor 64.

With the noise gate switch 61 thrown to engage contact 63a, the noise suppressing action of the circuit is eliminated, and it functions simply as an automatic volume control receiver, which action will now be described.

The cathodes of the tubes 7 and 17 are connected to ground through resistance 12a while the grids of the said tubes are not. However, the grid potential with respect to ground is fixed by the conductive connection of the grids of these tubes through conductor 70, resistance 53, radio frequency choke 23, and resistance 21 to ground, and the effective grid bias on these tubes is determined by the I. R. drop due to the space current 70 therein in resistance 12a plus the I. R. drop through resistance 53 (which may be neglected, since no appreciable current flow exists in resistance 53) and by the I. R. drop in resistance 21 due to the space current flowing in tube 25. 75

It will be understood that when space current flows in tube 25, the end of resistance 21 which is connected to the cathode, becomes more positive with respect to the other end, and the greater the space current in tube 25, the greater will be this I. R. drop. This drop comprises three components: (1), a radio frequency component which may be by-passed by condenser 22; (2), an audio frequency component which it is desired to amplify for operating the loud speaker; and, (3), a mean direct current potential which is utilized to obtain the automatic volume control action.

The radio frequency component is prevented from reaching the grids of tubes 7 and 17 by the action of the by-pass condenser 22 and also by the radio frequency choke 23. The audio frequency component is isolated from the grids of tubes 7 and 17 by resistance 53 and condensers 6 and 16, and it will be apparent the stronger the signal, and therefore the greater the space current in tube 25, the more negative the mean direct potential of the grids of tubes 7 and 17 will become with respect to their cathodes.

If now the various resistances be so chosen that when no signal is being received the tubes 7 and 17 are delivering maximum space current, and a signal is received, the increase in signal produces an increase in the negative bias of the tubes 7 and 17, which decreases their amplification.

For the strongest signals there will be the least amplification and for the weakest signals the greatest amplification in the tubes 7 and 17. Consequently, the system tends to maintain a constant volume level dependent upon the initial setting of the various elements, regardless of the strength of incoming signals.

As will be understood, the audio frequency component of the space current of tube 25 passes through condenser 29 and resistance 30 to ground through condenser 31, producing an audio frequency voltage drop in resistance 30 which, or the desired portion of which, is impressed upon the audio frequency amplifier tube 33, amplified by that tube, further amplified by tubes 35 and 36, and delivered to the voice coil of loud speaker 39.

Since the operation of the system from the output of tube 33 forms per se no part of my invention and is well known in the art, it is not described in detail.

It will also be noted that with switch 61 in engagement with contact 63a the grid of tube 33 is "self-biased" negatively with respect to the cathode thereof by an amount equal to the drop through resistance 94 due to the space current of tube 33, and is substantially independent of signal strength and consequently no selective noise-suppressing action is developed by the tube 33.

The noise suppression action of this circuit will now be described.

Referring now to Fig. 2, I have shown the long cathode space current characteristic of the gaseous discharge tube between the long cathode and anode plotted against voltage for a condition of constant ionization; that is to say, when anode 72 and short cathode 71 are connected through limiting resistor 74 across a source of voltage sufficient to maintain ionization within the tube, and it will be noted that if the voltage between the long cathode 73 and anode 72 increases up to a certain value, the space current increases very slowly and maintains a relatively small

value, which for practical purposes may be neglected.

At a certain voltage a very small increase in voltage produces a relatively sharp increase in space current, as indicated by the lower knee of the curve. Increased in voltage beyond this point produce relatively large and constant increases in space current until the tube begins to reach saturation. This characteristic is utilized to obtain magnified noise control in the circuit of Fig. 1. 10

It will be noted that when the switch 61 is thrown to engage contact 64a, the bias between grid and cathode of tube 33 includes the I. R. drop through resistance 65 and that through resistance 57 as well as that through resistance 94. 15

It will also be noted that resistance 57 is traversed by a current flowing from the positive to the negative side of the power pack, the magnitude of which may be controlled by adjustment of any one of the resistances 55, 56 and 57, and hence the I. R. drop through resistance 57 may be selected as desired. Also, the drop in potential between the positive side of the power pack, and upper, or negative terminal of resistance 51, may be controlled by varying the position of the 25 tap on resistor 55.

Assuming that the various resistances have been so chosen or adjusted that a satisfactory volume level is maintained for the weakest signal desired, it is possible to adjust the tap on resistor 55 until 30 the receiver just "goes dead". This will occur when the tube 33 is overbiased to an extent sufficient to render it unresponsive. Therefore, signals, and also noise, of lower strength will produce no response in the loud speaker. 35

If the value of the said resistance and the position of the tap on resistor 55 have been so chosen that when no signal is being received (and maximum space current is flowing in resistance 51), and the voltage between the long cathode 73 40 and anode 72 is just below the lower knee of the curve of Fig. 2, there will be no discharge on the long cathode 73 and no glow will appear thereon.

If now a stronger signal be tuned in, the negative bias on the grids of tubes 7 and 17 will be increased, as already explained, the current in resistor 51 will decrease, and the potential of the top point of resistor 51 will rise. This in turn increases the voltage effective between anode 72 and long cathode 73 above the lower knee of 50 the curve in Fig. 2 and, the cathode 73 will suddenly begin to take substantial space current, which flows from the top of resistance 51 to anode 72, to cathode 73, through resistance 65 to ground, (thereby making the upper terminal of 55 resistance 65 more positive than the lower terminal), thence through resistances 57, 56, a portion of 55, and resistance 51, back to the starting point.

This action, producing a sudden difference of 60 potential in resistance 65, the magnitude of which is sufficient to reduce the previous overbias on tube 33 to the normal operating bias, this tube will then amplify the audio frequency variations impressed upon it. 65

Also it will be noted that when the input circuit of tubes 7 and 17 is tuned to resonance with the incoming signal, the space current will be decreased to a minimum for that particular signal. Likewise the voltage drop through resistance 51 will be at minimum for that particular signal, and the voltage effective between long cathode 73 and anode 72 will be at maximum, and consequently the glow on cathode 73 will climb to a maximum point. 70 75

As resonance is passed, the space current of tubes 7 and 17 begins to increase, the voltage drop through resistance 51 begins to increase, the voltage effective across cathode 13 begins to decrease and the discharge recedes.

- 5 When the voltage reaches the lower knee of the curve in Fig. 2, the discharge suddenly decreases, the drop through resistance 65 decreases likewise, and the negative bias on tube 33 suddenly increases sharply, carrying the tube to its cut-off point, whereby it will be observed that as the receiver is tuned in the intervals on the dial between signals, the receiver will be unresponsive and as a signal is tuned in, the receiver will suddenly become responsive, the glow will appear on cathode 13 and will indicate by its maximum height when resonance has been reached. After resonance is passed, the reverse action occurs.

- 10 The tap on resistor 55 may be utilized for the purpose of providing a manual volume level control for selecting minimum audibility of signals desired to be heard. In the arrangement shown, the tap will be moved up when noise level is low and down when the noise level is high, thus requiring a stronger signal to "open" the receiver when noise is high.

- 15 For purposes of example and not of limitation, in the circuit shown, satisfactory results have been obtained when resistance 51 is of the order of 6,000 to 10,000 ohms, resistance 14 is of the order of 100,000 to 500,000 ohms, and resistance 65 of 10,000 to 25,000 ohms.

- 20 Referring now more particularly to Fig. 3, I have shown a slightly different modification. In this arrangement the receiver is arranged substantially as before, but it will be noted that some slight changes are made in the power supply apparatus. For instance, the field coil 38 of the loud speaker is utilized as a second choke on the positive side of the power supply, being connected by means of conductors 104 and 105 in series between the upper terminals of condensers 48 and 49. In this instance, resistances 100 and 101 are connected in series between the positive and negative points of the power supply, by means of which a substantially constant current flows through resistances 100 and 101, producing a substantially constant voltage drop therethrough. The anode of tube 33 is connected to a suitable point of positive potential and the cathode thereof is connected to a point on resistance 101.

- 25 When the noise gate switch 61 is thrown into engagement with contact 63a, thereby eliminating the noise suppressing action of the circuit, it will be noted that the grid return of tube 33 is taken to a point on resistance 101 more negative than the potential of the cathode, which point may be selected to provide the normal operating negative bias for tube 33.

- 30 In this instance the short cathode 11 of the gaseous discharge tube is connected to the switch contact 64a. The anode 12 is connected to resistance 51, as before, the other terminal of which is provided with a stop which may be adjustable on resistance 100.

- 35 The short cathode 11 may be connected through resistance 106 to conductor 102, representing the most negative point of the system, and the long cathode 13 is connected to conductor 107, which is also connected to switch contact 63a.

The noise suppressing action with the switch in the position shown is as follows:

- 40 The position of the tap from resistance 51, as before, serves the noise gate level, is adjusted

so that the voltage between the anode 12 and the short cathode 11 is just below the striking voltage. Therefore, no current flows through the gaseous discharge tube and the effective grid bias on tube 33 is the entire drop of potential between the negative end of resistance 101 and the point to which the cathode is connected, and this is chosen sufficiently great to overbias the tube 33 to cause plate current cut-off.

45 When a signal of sufficient strength is tuned in the plate current flow in tubes 7 and 17 decreases as before, causing the potential between the short cathode 11 and the anode 12 to rise. When the striking voltage is reached, a discharge takes place between the short cathode and the anode, causing an instantaneous jump in voltage between the short cathode and ground equal to the difference between the striking voltage and the working voltage of the tube, which is usually from 10 to 15 volts. This voltage appears across resistance 106 and thereby decreases the bias on the audio tube 33 by this amount, which is sufficient to reduce the over-bias on this tube to an amount sufficient to permit the tube to function.

50 The long cathode 13 of the gaseous discharge tube is connected to a point on resistor 101 about ten to fifteen volts positive with respect to ground, so that further decrease in the space current flowing through resistor 51 and the tendency thereby to increase the voltage between the anode 12 and the long cathode 13 causes the long cathode to take space current and the glow discharge appears on the long cathode and begins to climb, and reaches its maximum for resonance. This serves as a tuning indicator and simultaneously tends to prevent the grid bias on tube 33 decreasing unduly below the initial jump. Tuning of the receiver past the resonance point causes the current through resistor 51 to rise, thereby extinguishing the gaseous discharge tube 40 and causing the tube 33 to become again overbiased to plate current cut-off, silencing the receiver.

55 Referring now more particularly to Fig. 4, I have shown still a further modification of apparatus according to my invention in which, in this instance, no gaseous discharge tube is utilized for the purpose of noise suppression, that action being obtained by the use of only the tubes otherwise provided for normal operation of the receiver. In this arrangement the receiver circuit shown is substantially the same as before, but in this instance it will be noted that the field winding 38 of the loud speaker is connected by means of conductors 113 and 114 between the lower terminals of filter condensers 48 and 49.

60 As before, the plate return from tubes 7 and 17 are connected together through resistance 51 to the positive point of the power supply system, and it will be noted that in this instance, the plate of tube 33, instead of being connected to a point of relatively unchanging positive potential on the power pack, as in the previous arrangements, is connected to the negative end of resistance 51, to which the plates of tubes 7 and 17 are connected, and the plate of tube 33 therefore swings in potential. When no signal is being received, and the space current of tubes 7 and 17 is a maximum, the plate voltage on tube 33 is a minimum. Conversely, when incoming signals are being received, the space current of tubes 7 and 17 decreases, the drop through resistance 51 decreases, and the plate voltage rises. This change of plate voltage facilitates the blocking and unblocking of tube 33 under the control of 75

a varying grid bias, since the increase of plate voltage when signals are being received facilitates the unblocking of the tube, and the decrease when no signals are being received facilitates the blocking. The cathodes of the tubes 7 and 17 are connected together and through lead 54 and resistance 110 to ground. The cathode of tube 33 is likewise connected to ground, but the grid return in this instance is connected as before to the blade of noise gate switch 61. Resistances 111 and 112 are connected from resistance 110 to conductor 113 and it will be noted that a tap 59 may be provided for varying the value of resistance 112.

It will be noted that the anode current of the radio frequency amplifier tubes 7 and 17 flows through resistors 110, 111 and that portion of 112 included by the tap. The drop through resistor 110 serves to "self-bias" the tubes 7 and 17 to their normal operating value. The common point of resistances 110 and 111 may be grounded through conductor 52.

It will be noted that with the noise gate switch thrown to engage contact 63a, the resistance 111 is included in the grid circuit of tube 33, and this resistance is chosen of the desired value to maintain the normal operating bias on tube 33.

When, however, the noise gate switch 61 is thrown in the position shown, it will be seen that the bias on the grid of tube 33 includes the drop both through resistor 111 and that portion of resistor 112 included by the position of tap 59, and by moving the tap, the bias on tube 33 may be increased to a point sufficient to cause substantial plate current cut-off, at predetermined volume, or noise levels.

It will be noted that in this instance, although the bias on the audio tube 33 varies with the signal strength, it is possible to limit the variations of this bias to within tolerable values by proper choice of the values of the various resistors. The stabilizing action of the "self-bias" of the space current of tube 33 will prevent too small a grid bias.

If it is desired to magnify the noise suppressing action, or to provide a visual indicator for showing when the receiver is tuned exactly at resonance with an incoming signal, the apparatus shown in Fig. 5 may be added to that shown in Fig. 4 at the point indicated.

With the short anode 12 connected to the top of resistance 51 through conductor 80, the short cathode 71 may be connected through resistance 74 to conductor 114 and the long cathode 73 may be connected to the contact 64a by conductor 81. Resistance 82 is connected between conductor 81 and conductor 113.

With these additions and changes in structure, the operation of the system will now be described.

If the noise gate switch 61 be turned to engage contact 63a, the noise gate suppressing action will be eliminated and the tube 70 will function simply as a resonance indicator in the following manner.

The short cathode 71 and short anode 12 are connected respectively between the negative side of the power pack system and the negative side of resistance 51. Thus the effective voltage is the full voltage of the power supply system, which is essentially constant, less the voltage drop in resistance 51, which is a minimum at resonance.

The value of resistances 74 and 82 will be so chosen with respect to the characteristics of the tube that the gaseous interior of the tube is in

an ionized condition, and there may be a constant discharge between the anode 12 and the short cathode 71. Under normal conditions, with no signal being received, the voltage between the long cathode 73 and the anode 12 will be a minimum and no discharge occurs on the long cathode 73. However, when a signal is tuned in and the plate current decreases, the voltage effective between the long cathode 73 and anode 12 rises, causing a climbing glow to appear upon the long cathode 73, and this climbing glow reaches its maximum height when the signal is tuned to exact resonance. In general, the stronger the signal, the greater will be the potential across these electrodes and the greater will be the height of the climbing glow on the long cathode 73.

When the noise gate switch is rotated to the other position, that is, to engage contact 64a, the bias effective on tube 33 when no signal is being received includes the voltage drop through resistances 111 and 112, as already described with reference to Fig. 4, but it will be noted that the grid circuit also includes resistance 82. When no space current is being drawn by the gaseous discharge tube due to the action of resistance 51 already described, no current flows through resistance 82 and the effective grid bias on tube 33 will be that developed by the drop through resistances 111 and 112 due to the space current of tubes 7, 17 and 33.

When, however, the voltage effective between the long cathode 73 and the anode 12 increases to the point where the gaseous discharge tube begins to draw space current, this space current flows through the resistance 82 and produces a voltage drop of sufficient magnitude to overcome the overbias on tube 33 and to place the tube in operating condition.

As the receiver is tuned more closely to resonance, the voltage effective across the long cathode 73 and the anode 12 reaches a maximum and the glow appearing on the long cathode 73 reaches its maximum height. As resonance is passed, this voltage begins to decrease, the glow likewise begins to decrease and when this voltage becomes insufficient to maintain the gaseous discharge in tube 70, space current ceases to flow, the potential drop through resistance 82 drops to substantially zero and the effective negative bias on tube 33 is increased to the point of plate current cut-off.

In Fig. 6 I have shown an arrangement utilizing a gaseous discharge tube similar to the gaseous discharge tube used in Fig. 1, except that it comprises four electrodes instead of three, the fourth electrode being designated as 71a and the four electrodes being secured within a single press in a straight line, the electrode 71a being disposed on the opposite side of the electrode 73 from electrode 72. The connections are essentially the same in Fig. 6 as in Fig. 1 except for the changes shown, in which resistance 65a instead of being connected to electrode 73 is connected to electrode 71a and grounded at its lower end. Its upper end is connected to the contact 64a of the noise gate switch and the electrode 73 is connected directly to ground. Electrode 72 is connected as before to the junction of resistor 51 and conductor 50.

The arrangement of Fig. 6 has certain advantages over that of Fig. 1, in that a considerably sharper cut-off between a responsive condition and unresponsive condition may be obtained. That is to say, a smaller change of signal strength

will suffice to change the receiver from responsive to unresponsive condition and vice versa. In this arrangement it will be noted that resistor 65a corresponds to resistor 65 and serves to change the bias on audio tube 33 from plate current cut-off to operating condition. The operation involves the same fundamental principles as before, it being understood that when no signal is received the voltage existing between anode 72 and long cathode 73 is insufficient to produce a discharge between the said electrodes and under these conditions, although an ionizing discharge may take place between electrodes 71 and 72, no discharge takes place between electrodes 72 and 73 or between 72 and 71a. Consequently no current flows through resistor 65a and the audio tube 33 is overbiased to plate current cut-off.

When a signal is tuned in and the plate current of tubes 7 and 17 goes down to a value sufficient to cause a discharge to pass between electrodes 72 and 73, the discharge first passes to electrode 73 and instantaneously also to electrode 71a, thereby producing a voltage drop through resistance 65a, which serves to reduce the grid bias on tube 33 to an operative condition.

As the tuning approaches resonance the glow discharge on electrode 73 climbs as before to a maximum at resonance and after resonance is passed recedes and finally when the space current of tubes 7 and 17 increases sufficiently the voltage effective between electrodes 72 and 73 is no longer sufficient to maintain the discharge, which thereupon stops, and likewise the discharge from electrode 71a ceases, thereby overbiasing tube 33 to plate current cut-off.

In the arrangement shown in Fig. 7, I have shown the adaptation of a four electrode tube to the circuit of Fig. 3. In this case the electrode 71 is connected through resistor 125 to the common point of choke 46 and condenser 48. Electrode 72 is connected to the lower terminal of resistor 51, the upper terminal of which is connected as before. The long cathode 73 is connected directly to ground and electrode 120 is connected to the switch contact 64a and also through resistance 126 to ground. Switch contact 63a is connected as before.

The electrode 120 may be of greater length than electrodes 71 and 72 and of lesser length than the electrode 73 and its upper portion 122 may be bent to project toward electrode 73. The portion of electrode 120 which would otherwise be exposed within the tube may be enclosed with an insulating shield such as a glass tube 121 which may extend from the press nearly to the outer end of electrode 120.

By controlling the position of the end of electrode 120, that is, by making the electrode of greater or lesser length, it is possible to control the noise suppressing action very exactly, since it has been found that no current will pass to or from the electrode 120 until the discharge on electrode 73 has climbed to a point approximately in line with the end of electrode 120.

The operation of the system is somewhat similar to the operation of the system shown in Fig. 3, but differs therefrom in that the current passed by electrode 120 and which produces a voltage drop through resistor 126, is used to overcome the overbias on tube 33.

It will therefore be understood that as a signal is tuned in and as the plate current of tubes 7 and 17 goes down, a discharge takes place between the anode 72 and the long cathode 73.

Unlike the arrangements already described this

discharge does not immediately cause the tube 33 to be rendered responsive, since the discharge does not immediately jump to electrode 120. However, as the receiver approaches resonance and the glow begins to climb up electrode 73, it ultimately arrives opposite the end 122 of electrode 120 and at that time electrode 120 begins to draw current producing a voltage drop in resistance 126 which serves to reduce the overbias of tube 33 to an operating bias. As the receiver reaches resonance the glow on electrode 73 climbs still further and as the receiver passes resonance it begins to recede. When it passes the point opposite the end 122 of electrode 120 the discharge from electrode 120 ceases, the voltage drop developed through resistance 126 disappears, and the tube 33 is overbiased to plate current cut-off.

By the utilization of the principles embodied in this arrangement, it is possible to so adjust the receiver that a considerably smaller change in signal strength will open and close the receiver than with the other arrangements already described.

While I have shown and described certain preferred embodiments of my invention, it should be understood that these are by way of example and not by way of limitation and that modifications and changes may be made without departing from the spirit and scope of my invention, as will be understood by those skilled in the art. 50

I claim:

1. In a radio receiver, in combination, a signal selector, a circuit comprising a thermionic relay, means for impressing a grid bias on said relay such as to render said relay unresponsive to impressed impulses, and means comprising a gaseous discharge device for impressing on said relay a compensating bias of magnitude sufficient to render said relay responsive whenever the amplitude of incoming selected signals exceeds a pre-determined level.

2. In a radio receiver, in combination, a signal selector, a circuit associated therewith for receiving signals selected thereby and comprising a thermionic relay having an anode, a cathode, and a control electrode, means for biasing said control electrode with respect to said cathode to render said relay unresponsive to impressed signals, a gaseous discharge device, means for producing a discharge in said device whenever the amplitude of selected signals exceeds a predetermined amount, means associated with said discharge device for causing said discharge to produce a potential difference, and means for utilizing said potential difference to oppose said biasing means. 55

3. In combination, a work circuit comprising a thermionic relay, means for rendering said relay unresponsive to impressed impulses under predetermined conditions, a gaseous discharge device, means for producing in said device a climbing discharge, the height of which represents the magnitude of a desired function, and means for rendering said relay responsive whenever the length of said discharge exceeds a predetermined limit.

4. Control apparatus, comprising, in combination, a work circuit having a thermionic relay, means for impressing a potential on said relay to render it unresponsive, a gaseous discharge device having a pair of electrodes arranged to produce on one of said electrodes a discharge the length of which varies as a desired function, an additional electrode in said discharge device arranged to take current only for predetermined positions of said discharge, and means associated 70

with said additional electrode for impressing on said relay a potential to render it responsive when said additional electrode is taking current.

5. In a radio receiver, in combination, a gaseous discharge device having a relatively long electrode, means for producing a discharge on said electrode having a maximum length when said receiver is tuned to resonance with incoming signals, and means controlled by said discharge device for preventing response of said receiver to selected signals except when the amplitude of said signals exceeds a predetermined limit.

6. In electronic apparatus, in combination, a thermionic relay, means for impressing a potential on said relay to render it unresponsive, power supply apparatus for furnishing operating potentials to said relay, a gaseous discharge device having a pair of electrodes, one of which is relatively long, means for impressing between said electrodes a potential which varies as a predetermined function and of sufficient magnitude to produce a discharge on said long electrode, the length of which varies with said potential, an impedance in circuit with said discharge device for producing a potential derived from current passed by said discharge device, and connections for impressing said potential on said relay to oppose the potential rendering said relay unresponsive.

7. In a radio apparatus, in combination, an amplifier, means for decreasing the gain of said amplifier in accordance with the amplitude of received signals, whereby said amplifier tends to maintain a constant output volume level, a second amplifier, arranged to amplify the output of said first amplifier, means for biasing said second amplifier to plate current cut-off, a gaseous discharge device, means for impressing across said device a variable potential which is a maximum when the circuit of said first amplifier is in resonance with received signals, an impedance in circuit with the space path of said device, and connections between said impedance and said second amplifier for opposing said first biasing means.

8. In a radio receiver, in combination, a signal responsive device comprised of a vacuum tube amplifier having an anode, a cathode, and a control electrode, means for supplying signals to said device, including means for selecting the frequency of supplied signals, means for supplying plate and grid voltages to said amplifier to render the same unresponsive when no signals are being received, and means for producing a change in both said voltages to render said amplifier responsive when signals of predetermined strength are being received.

9. In a radio receiver, in combination, a signal responsive device comprised of a vacuum tube amplifier having an anode, a cathode, and a control electrode, means for supplying signals to said device, including means for selecting the frequency of supplied signals, means for supplying plate and grid voltages to said amplifier to render same unresponsive when no signals are being received, and means for producing an increase in plate voltage when signals of a predetermined strength are being received.

10. Radio receiving apparatus, comprising, in combination, a radio frequency amplifier system having at least one vacuum tube amplifier having a cathode, an anode, and a control electrode; a detector and an audio frequency amplifier having a cathode, an anode, and a control electrode; an impedance associated with said detector to provide a voltage drop which increases with the

strength of incoming signals; a connection between said impedance and the control electrode of said radio frequency amplifier for causing the same to become increasingly negative with increase in signal strength; an impedance in the space current path of said radio frequency amplifier tube, and a connection between the control electrode of said audio amplifier and said last named impedance for causing said control electrode of said audio amplifier to become less negative with respect to its cathode with increase in signal strength.

11. Radio receiving apparatus, comprising, in combination, a radio frequency amplifier system having a cathode, an anode, and a control electrode, a Fleming valve detector and an audio frequency amplifier having a cathode, an anode, and a control electrode, an impedance connected between the electrodes of said detector and traversed by a current which increases with the strength of incoming signals, a connection between said impedance and the control electrode of said radio frequency amplifier for causing the same to become increasingly negative with increased signal strength, an impedance in the space current path of said radio frequency amplifier tube and a connection between the control electrode of said audio amplifier and said last named impedance, causing the control electrode of said audio amplifier to become less negative with respect to its cathode with increase in signal strength.

12. Radio receiving apparatus comprising, in combination, a radio frequency amplifier system having a cathode, an anode, and a control electrode, a Fleming valve detector and an audio frequency amplifier having a cathode, an anode and a control electrode, an impedance connected between the electrodes of said detector and traversed by a current which increases with the strength of incoming signals, a connection between said impedance and the control electrode of said radio frequency amplifier causing the same to become increasingly negative with increased signal strength, a pair of impedances connected in the plate circuit of said radio frequency amplifier, a connection between one of said impedances and the plate of said audio frequency amplifier, and a connection between the other of said pair of impedances and the control electrode of said audio frequency amplifier whereby the control electrode of said audio frequency amplifier becomes less negative and the anode of said audio frequency amplifier becomes more positive with respect to its cathode on receipt of signals of predetermined strength.

13. In a radio receiver, in combination, a radio frequency amplifier system having a cathode, an anode and a control electrode, a detector and an audio frequency amplifier, means for causing the space current of said radio frequency amplifier to decrease with increasing signal strength, a gaseous discharge device having a relatively long electrode for producing a discharge the length of which on said electrode increases with increasing signal strength, a second electrode associated with said long electrode and arranged to take current only when the length of discharge of said long electrode reaches a predetermined value and means controlled by said second electrode for modifying the operation of said receiver.

14. In a radio receiver, in combination, a thermionic relay, means for impressing a potential on said relay to render it unresponsive, a gaseous discharge device having a pair of electrodes arranged

- 5 to produce on one of said electrodes an expanding discharge the size of which varies as a desired function, an additional electrode in said discharge device arranged to take current only for predetermined positions of said discharge, and means associated with said additional electrode for impressing on said relay a potential to render it responsive when said additional electrode is taking current.
- 10 15. In a radio receiver, in combination, a signal selector, a circuit comprising a thermionic relay, means for impressing a grid bias on said relay such as to render said relay unresponsive to im-

pressed impulses, means comprising a gaseous discharge device for impressing upon said relay a compensating bias of magnitude sufficient to render said relay responsive whenever the amplitude of incoming selected signals exceeds a 5 predetermined level, said gaseous discharge device comprising a pair of keep-alive electrodes, a primary discharge electrode and a secondary discharge electrode arranged to draw current only when said primary discharge electrode draws current. 10
